DESIGN FOR A DRAFTING IMPLEMENT

Robert W. Musgrave, Alhambra, Calif.

Application January 23, 1946, Serial No. 125,869

Term of patent 14 years

(Cl. D52—1)

To all whom it may concern:

Be it known that I, Robert W. Musgrave, a citizen of the United States, residing at Alhambra, in the county of Los Angeles, State of California, have invented a new, original, and ornamental Design for Drafting Implement, of which the following is a specification, reference being had to the accompanying drawing, constituting a part hereof.

Fig. 1 is a plan view of a drafting implement, showing my new design, and

Fig. 2 is a transverse section taken on line 2—2 of Fig. 1.

I claim:

The ornamental design for a drafting implement, substantially as shown.

ROBERT W. MUSGRAVE.
